UNITED STATES PATENT OFFICE.

NELS EKBERG, OF ST. PAUL, MINNESOTA.

DUMP-CAR.

Specification of Letters Patent. Patented Aug. 16, 1921.

1,387,968.

Application filed March 24, 1921. Serial No. 455,079.

To all whom it may concern:

Be it known that I, NELS EKBERG, a citizen of the United States, residing at St. Paul, in the county of Ramsey and State of Minnesota, have invented a new and useful 5 Dump-Car, of which the following is a specification.

My invention relates to dump cars of the class riding on a track and employed for 10 hauling and dumping earth, either for the purpose of leveling down some hill or for filling up some place that is too low; and the main object is to provide a dump car of such improved construction that it will require no side doors to be opened during the 15 dumping and that the car body during the dumping will move laterally outward and thus dump the earth some distance away from the track.

20 This and other objects I attain by the novel construction and arrangement of parts illustrated in the accompanying drawing, in which:—

Figure 1 is a side elevation of my improved dump car shown as standing on a 25 track.

Fig. 2 is an end elevation of Fig. 1 showing in dotted line also the car body in dumped position.

30 Fig. 3 is an enlarged top view of the right hand end portion of the car in Fig. 1 with the chain omitted.

Fig. 4 is an elevation of Fig. 3 with the chain restored.

35 Fig. 5 is a sectional elevation of the rolling gear and rack supporting the dump car body, as on line 5—5 in Fig. 6.

Fig. 6 is a section on line 6—6 in Fig. 5.

40 Fig. 7 is an enlarged section on line 7—7 in Fig. 4. Fig. 8 is a section on line 8—8 in Fig. 3.

Referring to the drawings by reference numerals, 1 designates the ties and 2 the rails of a track upon which roll the regular 45 flanged supporting wheels 3 of a truck frame 4 having journal bearings 5 for the axles 6 of the wheels.

Secured upon the frame 4 are timbers or other longitudinal bars 7 to which the draft 50 bars (not shown) are secured. Secured upon the bars 7 are two transversely disposed supporting racks 8, one near each end of the truck, and on a long car there may be a similar support 8^a without rack teeth

and with a blank supporting segment 8^b 55 resting on it to support the middle of the car body 9. Said body is further supported and guided by two toothed sectors or mutilated gears 10, secured at 11 up under the car body or box and having fixed in them short 60 shafts 12, which are guided in horizontal slots 13 in vertical flanges 14 projecting up from the sides of the racks 8.

The car body 9 is dished or almost segmental in cross section, and being made of 65 sheet metal it is stiffened by transverse bracing bars 15 and longitudinal bars 16 and 17. The latter bars, one at each side of the car, are each preferably made of channel iron turned with its flanges 18 and 19 outward. 70 Pivotally secured to each of said bars 17 are three legs 20 whose lateral swinging movement is limited by their contact with the flanges 18 and 19. To the lower ends of said 75 three legs is secured a foot bar 21, preferably made up of two angle bars as shown in Fig. 2. Said foot rails 21 when the car is being dumped get in contact with the ties 1 of the track and thereby prevent injurious strain on the car body and its connection 80 with the truck. The ends of bar 21 are runner shaped to prevent their engagement with the ties or the ground. 21^a are braces to resist endwise pressure on the rails 21.

The car body is held in standing position 85 and released therefrom by the following means: Each end of the car has a chain 22 extending across the end of the truck and is there guided by two flanged pulleys 23 mounted on short shafts 23^a in metal frames 90 23^b (see Figs. 4 and 7) and held stretched by a rolling weight 24 mounted on a swinging arm 25 (see Fig. 2). The ends of the chain are brought upward and secured at 26 one near each corner of the car body. 95

Fixed on each chain 22 are two cross bars 27 (best shown in Figs. 7 and 8) forming opposite lateral projections on the chain. When the car body is in normal standing position said projections are engaged at their 100 upward sides by the lower and slightly concaved or curved sides of two arms 28 of a locking member having four arms 28—29 and fixed on a short rock shaft 30 having a weighted lever 31, which when the arms 28 are engaged by dogs 32, stands up as in dotted line 31^a in Fig. 4. Said dogs 32 are fixed two at each end of the rock shaft 33 ex-

tending from end to end of the truck frame and at each end provided with a hand lever 34 which normally rests on a supporting peg 35 and by its weight holds the dogs engaged and thereby the car body locked in standing position. The two lower arms 29 have their ends pointed and curved so that when they rest against the shaft 23^a or a hub 23^c of the pulley 23 the bar 27 in its 10 upward movement will not engage but pass over them.

In the operation of the car, when the car is to dump a load of earth, gravel, sand, rocks or other materials, the operator raises 15 one of the hand levers 34, so as to disengage the dogs 32 from the arms 28 on that side of the car; while thus holding the dogs disengaged he gives the car body the necessary push to cause it to tip over toward the 20 side having the dogs still engaged. The car body now rolls to the position shown in dotted line in Fig. 2 and empties out its load. When this tilting of the car body started, the fingers 27 on the chain raised 25 the arms 28 of the locking members at that side of the car into vertical position, where they are held by the arms 31 resting on the peg 35. On the other side of the truck the fingers 27 move idle along with the horizontal run of the chain, and as the car body is raised again they move to their regular 30 position under arms 28. During the latter movement the released fingers 27 return downward and finding arms 28 in raised position pass by them, and descending upon the now horizontal arms 29 throw the latter down to their downward position and cause the arms 28 to glide with their ends down the inclined faces 32^a (see Figs. 4 and 8) of 35 the dogs and thereby automatically raising the levers 34 slightly and engaging the dogs, and causing arm 31 to raise to position 31^a.

To dump the car to the other side simply 40 operate the levers 34 at the side of the car opposite from that just described as operated.

If so desired the shafts 30 may be extended all along the car truck and the levers 31 operated by hand, but this will not be necessary if the car body is always returned 45 to standing position with sufficient speed to cause levers 31 to rise from the impetus given them by fingers 27 striking arm 29 downward.

It will be understood that as the cog 50 wheels 10 roll on the racks 8 the car body, and thereby the load, is carried and dumped such a distance beyond the track as may be predetermined by the size of the gears. Also 55 that each foot rail 21, with hangers 20, is by the flange 18 caused to come down in position on the ties with the hangers vertical, and the opposite rail 21 can not strike the side of the car body on account of the flange 19.

In Fig. 6 is best shown that each rack 8 has an upstanding blank rib 8^a guiding in a groove 10^a in the gear 10 so as to resist endwise pressure on the car body even if the flanges 14 do not fit against the sides 70 of the gears.

In Figs. 3 and 8 22^a designate notches in the frames 23^a for the chain during the dumping action.

Having thus described my invention what 75 I claim is:—

1. A dump car having a laterally tiltable body composed of a single member of segmental form in cross section so as to hold the load when in normal position and dump 80 it automatically when tilted to either side, said body having hangers pivoted one set to each side to swing to and from the same, a foot rail secured to each set of hangers and arranged to stop the tilting of the car body 85 when the rail gets in contact with the track on which the car stands.

2. The structure specified in claim 1 and means for limiting the swinging movement of said hangers.

3. The structure specified in claim 1, said foot rail having its ends curved upward from the surface it is to contact with.

4. In a dumping car having a truck frame and a body mounted thereon to tilt and 95 dump toward either side, means for holding said body in normal position and for releasing it when it is to be dumped, said means comprising a special corner frame fixed at each of the four corners of the main 100 truck frame, and mounted in each of said corner frames, a four-armed tiltable chain locking device, two dogs arranged to automatically engage the locking device, a hand lever for disengaging the dogs, a weighted 105 lever on the locking device for holding it in unlocked position, a guide pulley in each corner frame, a chain extending horizontally under and guided by said pulleys and having its ends brought upward and secured to 110 adjacent corners of the body, said chain having catches arranged to be locked against upward movement by the upper arms of the locking devices and to raise said upper arms when they are released from the dogs, said 115 catches on the chains also arranged on their downward movement to strike the lower arms of the locking devices and thereby restore the upper arms to locked position.

5. The structure specified in claim 4 and 120 an automatic stretching device for holding said chain stretched into guiding contact with the pulleys.

6. The structure specified in claim 4 and two rock shafts extending one along each 125 side of the truck frame and secured in said hand levers and in all the dogs in one side of the truck frame.

7. The structure specified in claim 4 and two rock shafts extending one along each 130

side of the truck frame and having secured to them all the locking devices and the weighted levers of same on one side of the frame.

5 8. In a mechanism of the kind described, a reciprocating chain having lateral catches by which to stop its movement, a tiltable

locking device having arms arranged to engage the catches, and means for locking the locking device, said arms on the locking device having each a curved side facing the catch on the chain. 10

In testimony whereof I affix my signature.

NELS EKBERG.
